Fig.2.

INVENTOR.

Fred Ashworth
By his Attorney,
Nelson W. Howard

UNITED STATES PATENT OFFICE.

FRED ASHWORTH, OF WENHAM, MASSACHUSETTS, ASSIGNOR TO UNITED SHOE MACHINERY CORPORATION, OF PATERSON, NEW JERSEY, A CORPORATION OF NEW JERSEY.

MACHINE FOR FORMING WEDGE-SHAPED ARTICLES.

Original application filed March 21, 1919, Serial No. 284,058. Divided and this application filed July 28, 1925. Serial No. 46,598.

To all whom it may concern:

Be it known that I, FRED ASHWORTH, a citizen of the United States, residing at Wenham, in the county of Essex and Commonwealth of Massachusetts, have invented certain Improvements in Machines for Forming Wedge-Shaped Articles, of which the following description, in connection with the accompanying drawings, is a specification, like reference characters on the drawings indicating like parts in the several figures.

This invention relates to machines for treating sheet material having opposite edges differing in thickness and is illustrated as embodied in a machine designed for forming wedge-shaped lifts for heels of boots and shoes.

In various manufacturing operations involving the handling of blanks or articles characterized by having opposite edges of different thicknesses, of which wedge lifts are typical, problems have arisen when, for example, it has been desired to stack the lifts or other articles in magazines and to remove successive articles from the magazines automatically for presentation to various operating instrumentalities. If articles such as wedge-shaped heel lifts are stacked in a magazine with their thin edges pointing all in one direction, the corresponding surfaces of the stacked lifts are not parallel and consequently the lifts tend to clog the magazine, rendering subsequent feeding of lifts from the magazine difficult and uncertain. If such lifts be placed in a magazine with their thick and thin edges arranged alternately in opposite directions, then complex mechanism must be provided to effect the feeding of the lifts from the magazine.

I have discovered that the difficulties above mentioned may be avoided by forming wedge-shaped articles with projections on their thin edge portions, each projection being of sufficient height to make the total thickness of an article at a projection substantially equal to the maximum thickness of the article. When formed in this manner, the articles may be stacked with their thin edges extending in the same direction because the said edges will be so spaced relatively to each other that the correspond-

ing surfaces of the articles will be in substantially parallel relation. This method of forming and stacking articles, such a stack of articles, and the novel articles themselves, are disclosed and claimed in my application Ser. No. 284,058, filed March 21, 1919, of which the present application is a division.

In view of the foregoing, an object of the present invention is to provide a machine by the use of which wedge-shaped heel lifts or other articles having similar characteristics may be provided with projections or corrugations such as those above referred to.

To this end, and in accordance with features of the invention, the illustrated machine is provided with mechanism for feeding material such as leatherboard or other sheet material adapted to be cut into heel lifts to mechanism organized to form projections along one margin of the material. In the illustrated embodiment of the invention, a strip of sheet material wedge-shaped in transverse cross-section is fed by rolls, one of which is provided with dies or projections arranged to form projections along the thin edge margin of the strip as it is fed to cutting mechanism operating to cut wedge-shaped lifts from the strip in such a manner that each lift is provided along its thin edge with one or more such projections.

It will be apparent that when projections are formed in this manner, if the corresponding projections of successively stacked lifts were alined, the projections would nest. That is, the inner surfaces of the stock forming the projections would fit the outer surfaces of adjacent projections, thus preventing obtaining the desired parallelism of the lifts. To prevent this result, in accordance with another feature of the invention, the dies on the feed roll are so spaced relatively to the width of the lifts to be cut that the projections on successive lifts will be staggered with relation to each other.

While the machine shown in the drawings constitutes a preferred organization for so forming wedge-shaped lifts or other articles as to obtain the desired result, it should be understood that in various aspects the invention is not limited to embodiment in the particular type of mechanism herein illus-

trated or to forming projections of the particular kind or in the manner in which they are formed by the use of this machine.

Other objects and features of the invention will be apparent from the following detailed description and will be pointed out in the claims.

In the drawings,

Fig. 1 is a perspective view, partly in section, of a wedge lift forming machine; and

Fig. 2 is a diagrammatic representation of a portion of material being operated upon with the formed lifts left in position in the sheet material.

In the illustrative embodiment of the invention, feed rolls 4 and 6 feed strip material 8 intermittently to a dieing-out mechanism consisting of a heel lift die 10 and a co-operating cutting block or presser member 12 mounted on a reciprocable member 14, though any other suitable form of dieing-out mechanism may be substituted for that shown. At each reciprocation of the block 12 relatively to the die 10 a heel lift 16 is died out from the strip material 8.

The material 8 may be of leather, leather-board or other sheet material, is wedge-shaped in cross-section, and is adapted for the production of wedge heel lifts.

The rolls 4 and 6 are arranged to engage opposite sides of the material 8 for feeding the latter to the dieing-out mechanism, are mounted respectively on shafts 18 and 20 arranged in parallel relation and are driven by suitable mechanism (not shown) from the same source of power.

The means for operating upon the material to produce projections comprises, in the present construction, dies or projections 22 extending from the periphery of the feed roll 4 in such position as to co-operate with a recess, shown as a groove 24 in the periphery of the other feed roll 6. The height of a die 22 is such that a projection formed by it on a lift increases the thickness or height of the thin portion of the lift at a projection substantially to the thickness of the thick edge of the lift.

The dies 22 are pyramidal and the sheet material, as it passes between the feed rolls, is acted upon in such a way as to provide projections 26 having rectangular bases.

It will be observed, from an inspection of Fig. 2, that while the projections 26 are regularly spaced on the thin portion of the sheet material 8, in the completed heel lifts the projections are variously positioned therein. To accomplish this result, the dies 22 are arranged on the roll 4 in such manner that the projections 26 formed by the dies are so spaced that the distance between any two projections is not commensurate with the distance between corresponding points in consecutive heel lifts

along the line of projections. That is, the projections on the lifts are formed in such manner that, when lifts are stacked with their thin edges pointing in the same direction, projections on successive lifts will be in staggered relation. This insures a different position of projections for successive heel lifts.

The spacing of the feed roll dies 22 may be so arranged that lifts of different sizes 75 may be died out, merely by changing dies 12, without securing the same positioning of projections in consecutive lifts. For example, a lift formed by the die 12 in Fig. 1 may have three projections while lifts of 80 the size shown in Fig. 2 may have only two complete projections.

In the operation of the machine above described, sheet material 8 is moved toward the die 10 by means of the feed rolls 4 and 6, the projection 26 being formed on the material, as it is fed by the co-operating dies 22 and groove 24. The presser member 12 is reciprocated to effect dieing-out operations to form heel lifts from the material 90 as it is moved over the die.

Having described my invention, what I claim as new and desire to secure by Letters Patent of the United States is:—

1. In a machine of the class described, a feed roll for feeding sheet material, dies on the feed roll for producing projections along one edge of the sheet material, and means for cutting heel lifts from said material to include one or more projections on each lift, the spacing of the projections being such as to insure that the projections on some of the lifts are positioned differently from those on other lifts.

2. In a machine of the class described, means for producing projections along one edge of sheet material, and means for cutting blanks from said material to include one or more projections on each blank, the construction and arrangement of said means being such as to insure that the projections on some of the blanks are positioned differently from those on other blanks.

3. In a machine of the class described, means for feeding sheet material, means for producing spaced projections on the material, and means for cutting blanks from said material in such manner that the projections on some of the blanks are positioned differently from those on other blanks.

4. In a cutting machine, means for forming projections in the thin edge portion of a strip of material of such a nature that a section through the thin edge portion and through a projection therein is of the same height as the thick edge of the strip, and means for so cutting blanks from said strip that each blank contains one or more of said projections.

5. In a machine of the class described,

means for feeding sheet material, means for forming projections on one side of said material simultaneously with the feeding operation, and means for subsequently cutting out blanks from said material in such manner that the projections on some blanks are positioned differently from those on other blanks.

6. In a machine of the class described, means for feeding sheet material of varying thickness in cross-section, and means for forming projections on a thin portion of said material such that the total thickness of the material at a projection is increased substantially to the maximum thickness of the material.

7. In a cutting machine for operating on sheet material having opposite edges differing in thickness, means for forming projections on the thin edge portion of the material of such a nature that the total thickness of the thin edge portion at a projection is substantially the same as the thickness of thick edge of the strip, and means for so cutting blanks from said strip that each blank contains one or more of said projections.

8. In a machine of the class described, cooperating rolls for feeding a strip of material and for forming projections on said material, one of said rolls having projection-forming members on its periphery and the other roll having a peripheral groove to receive said members, and means comprising a die for cutting wedge-shaped heel lifts from

said material in such manner that the projections are positioned differently on successive lifts.

9. In a machine of the class described, a member having dies thereon, a second member having a recess therein and arranged for co-operation with the first-mentioned member to produce projections on material introduced between said members, and means for cutting blanks from the material in such manner that projections are positioned differently in successive blanks.

10. In a machine of the class described, feed rolls for feeding sheet material of irregular cross-section, projections on one of the feed rolls for forming projections on a thin portion of the material, and means for cutting blanks from the material such that each blank contains one or more projections, the height of the projections on the feed roll being such that the projections formed on a blank increase the height of the thin portion of the blank substantially to the maximum thickness of the blank.

11. In a machine of the class described, means for providing wedge-shaped heel lifts with projections on their thin edge portions, each projection being of sufficient height to make the total thickness of a lift at a projection substantially equal to the maximum thickness of the lift.

In testimony whereof I have signed my name to this specification.

FRED ASHWORTH
